UNITED STATES PATENT OFFICE.

PETER J. FANNING, OF PROVIDENCE, RHODE ISLAND.

POWER MECHANISM.

1,172,692.

Specification of Letters Patent. Patented Feb. 22, 1916.

Application filed November 4, 1914. Serial No. 870,175.

To all whom it may concern:

Be it known that I, PETER J. FANNING, a citizen of the United States, residing at Providence, in the county of Providence and 5 State of Rhode Island, have invented certain new and useful Improvements in Power Mechanisms, of which the following is a specification.

My invention relates to such power mechanisms as engines, motors, air compressors, 10 blower and pumps.

The essential objects of my invention are to insure a tight contact of the disk with the casing; to equalize the wear on the faces 15 of the former; to obtain a continuous flow of the fluid, liquid, or air; to minimize the number of valves or entirely dispense therewith; to avoid leakage of fluid, liquid, or 20 air during compression; and to attain these ends in a structure which is inexpensive and simple in construction and operation.

Further objects of my invention will appear from an examination of the drawings and following description.

25 To the above recited and suggested ends my invention consists in such parts and combinations of parts as fall within the scope of the appended claims.

In the accompanying drawings which 30 form a part of the specification, and in which is shown merely a preferred form of embodiment of my invention, Figures 1 and 2 are side and front elevations respectively of a pump or air compressor embodying the 35 invention, Figs. 3 and 4, a partial section on line *w*, *w*, of Fig. 2, and a section on line *x*, *x*, of Fig. 1 respectively, Fig. 5, a plan view of the same showing the upper portion cut away, Figs. 6 and 7, sections on 40 *y*, *y*, and *z*, *z*, respectively of Fig. 4, Fig. 8, a perspective view of the abutment members, and Fig. 9, a side elevation of the disk.

Like reference characters indicate like 45 parts throughout the views.

In the embodiment of the present invention the assemblage of parts may comprise in a general way a casing comprising a base 10, a cylindrical body or ring 11 provided with annular flanges 12 to which are attached by screws 13, 14, heads or plates 17 and 18 respectively. The heads are respectively provided with laterally extending vertically disposed extensions 19 and 20 in alinement with each other and having parallel side walls 21, 21 and 22, 22. The respective extensions are completed by plates 23 and 24 integral with the extensions or attached thereto by screws 25 and 26 respectively. These extensions form guideways or oblong chambers 27 and 28. The 60 parallel heads or walls 17 and 18 together with the rim or body 11 form a substantially cylindrical operating space or chamber 30. Opening into this chamber at 31 and 32 respectively are passages 33 and 34 65 in corresponding walls 21 and 22 respectively, which open in turn at 35 and 36 at points in the outer ends of the chambers 27 and 28 respectively, as shown in Fig. 5. The casing is completed by an integral enlargement or head 38 upon the top of the body 11 provided with oppositely disposed threaded orifices 39 and 40 in alinement with each other in which are threaded the ends of the intake or suction pipe 41 and the discharge pipe 42 respectively. Passages 43 and 44 extend from the ends of the respective pipes into passages 45 and 46 formed by transversely disposed parallel grooves traversing the inner face of the member 11, 80 and therefore opening into the chamber 30.

Slidably mounted in the wings 19 and 20 respectively are the abutment plates 47 and 48 of similar shape and of substantially rectangular outline. Their combined length 85 being less than the combined length of the wings, it will be noted by reference to Fig. 3 that resultant spaces are formed at the outer ends of the chambers 27 and 28; and by reference to Fig. 5 it will be further 90 noted that the passages 33 and 34 open into said spaces at 35 and 36 respectively.

The adjacent inner ends of the plates 47 and 48, at their upper portions, have rectangular shoulders or projecting portions 49 and 50, and immediately beneath these the adjacent edges of the plates are transversely rounded, as at 51 and 52. The bottom edges of the plates have channels or concavities 53 and 54 to permit an intimate registration 100 with the surface of the shaft 56 of the machine. This shaft is journaled in the lower portions of the wings 19 and 20 and is concentric with the chamber 30 through which it passes. It projects through an opening 57 in the end plate 23 of the casing, and has fixed thereto the driving or driven wheel 58 which, in the present instance, is driven from any convenient source of power. The plate 47 is provided with an opening 105 59 having threads 60 extending through the shoulder 49. The plate 48 also has a longi-

tudinally disposed opening or channel 61, in alinement with the first mentioned opening or channel, extending through the shoulder 50, and opening at its outer end in a vertical groove or channel 63 in the outer end face of the plate and extending midway thereof. A longitudinally disposed orifice 64 extends from the lower end of the channel 63. A rod 66 has its end provided with a thread 67 to loosely engage the thread 60 of the opening 59, and extends through the channel 61. An arm 68 on this rod rests in the channel 63 and contacts with one end of a helical spring 70 seated in the orifice 64. The upper margins of the abutment plates 47 and 48 are a sliding fit not only in the wings 19 and 20, but through a transverse groove or guideway 71 in the head portion 38 of the body 11 midway between the grooves 45 and 46 of the latter.

Integral with or brazed to the power shaft 56 within the chamber 30 is a disk 72, whose peripheral margin is inclined to the axis of the shaft, and whose peripheral face 73 is cylindrical and concentric with the shaft. The thickness of the disk wall is substantially the same throughout, and its side or operating faces 75 and 76 are at every radial point at right angles to the axis of the shaft. The right angular character of the radial points of the disk 72 are more clearly apparent in Fig. 3, wherein the disk is shown in full sectional lines at an extreme of lateral travel; and in broken lines, its position at the end of its complete revolution. Hence by rotating the shaft there is a lateral reciprocation in opposite directions to each other of those parts of the disk above and below the shaft; or an oscillation of the disk. The disk operating faces 75 and 76, as shown in Fig. 5, are provided with the lateral convex swells or shoulders 79 and 80 respectively, upon opposite sides of the shaft, these swells being more pronounced adjacent the shaft. Complementary of the swells are resultant lateral concavities or depressions 81 and 82 at those portions of the disk directly opposite the respective swells. The swells 79 and 80 are preferably provided at their apices with slightly flattened surfaces 85 and 86, as shown in Fig. 4.

The disk in its rotation or oscillation travels through the space 88 between the rounded edges 51 and 52 of the abutment plates, and in continuous contact therewith; the slight irregularities of thickness of the operative disk faces due to the flat faces 85 and 86, when such faces are present, being compensated for by the spring 70 acting on the arm 68 and rod 66 whereby the abutment members 47 and 48 are pressed toward each other against the opposite surfaces of the disk.

The operation of the mechanism in performing its functions as an air compressor

is as follows:—The disk rotates in this instance in the direction of the arrows shown in Figs. 4 and 5. This rotation both reciprocates the abutment and sucks the air from its source of supply through the intake port comprising the pipe 41, passage 44, and channel 46 into one side of the operating chamber 30. Simultaneously compression is taking place in the opposite side of said chamber whence the air is expelled through the outlet port comprising the channel 45, passage 43 and pipe 42. For the purpose of minimizing the number of views, the disk in Fig. 3 is shown at its extreme lateral travel, and in Fig. 5, at an intermediate position. In the latter figure it will be noted that the portion of the chamber 30, at one side of the shaft 56 and the abutment 51 and 52, is divided by the disk, whose peripheral surface is in slidable contact with the wall 11, into two compartments 87 and 89, and the half of the chamber 30 at the other side of the abutment, into two air tight compartments 90 and 91. Participating in the boundary of these compartments are the shoulders 79 and 80, which are in continuous contact with the side walls of the casing during the rotation of the disk. The compression of the air is wholly in the compartments 90 and 91, and the suction or vacuum is performed exclusively in the compartments 87 and 89.

It will be observed that in both sets of compartments the air is operated upon by both faces of the disk rather than upon one surface, a result not attainable by worms or spiral flanges. Communication is constant between the compression compartments by the channel 45, and between the suction compartments, by the channel 46. To avoid the accidental escape of the air from the compression compartments intermediate the disk and the inner ends of the partition plates 47 and 48, and to avoid the cramping of these members, communication is afforded from the compartments 90 and 91, through the passages 33 and 34, to the spaces 27 and 28 at the ends of said members. Hence the degree of inward pressure upon the outer ends of the members balances the pressure in the compartments seeking escape. The spring thus performs its function effectively and under no strain. The mechanism may be operated with equal facility by the use of the parts 45, 43 and 42 as an inlet port, and the parts 41, 44, and 46 as an outlet port, in which case the direction of rotation of the disk is reversed.

When the mechanism is employed as an engine or motor obviously the initial power is not through the shaft 56, but the fluid under pressure enters through one of the ports and exhausts through the other port.

I have entered into a detailed description of the construction and relative arrangement

of the parts embraced in the present embodiment of my invention in order to impart a full, clear, and exact understanding of the same. I do not desire, however, to be understood as confining myself to such specific construction and relative arrangement of parts, as such changes or modifications may be made in practice as fairly fall within the scope of my invention as claimed.

10 What I claim is,—

1. In a power mechanism, the combination of a casing provided with a power chamber, a shaft rotatably mounted in the casing, an inclined disk in the chamber upon the shaft provided with parallel side faces, and a partition comprising two plates yieldingly connected with each other slidably mounted in the casing with their adjacent ends in contact with the side faces of the disk.

20 2. In a power mechanism, the combination of a casing provided with a power chamber, a shaft rotatably mounted in the casing, an inclined disk in the chamber upon the shaft provided with parallel side faces, and a partition comprising two plates yieldingly connected with each other slidably mounted in the casing provided with rounded adjacent ends in contact with the side faces of the disk.

30 3. In a power mechanism, the combination of a casing provided with a power chamber, a shaft rotatably mounted in the casing, a disk in the chamber upon the shaft inclined relatively thereto and provided with side faces parallel to each other, and at every point at right angles to the shaft, and a partition comprising two plates detachably connected with each other resting upon the shaft with their inner ends adapted to contact with the side faces of the disk, and resilient

means for forcing the plates against said faces.

4. In a power mechanism, the combination of a casing provided with a power chamber and with lateral chambers opening into the power chamber, a shaft rotatably mounted in the casing transversely of the power chamber, an inclined disk in the power chamber upon the shaft, and a partition comprising two plates detachably connected with each other resting in the lateral chambers upon the shaft and of less length than the lateral chambers with their inner ends in contact with the faces of the disk, said casing being provided with passages extending from the power chamber to the outer end portions of the lateral chambers.

5. In a power mechanism, the combination of a casing provided with a power chamber, a shaft rotatably mounted in the casing, a disk upon the shaft in the chamber inclined relatively to the shaft and provided with side faces annularly curved and radially parallel with each other at right angles to the shaft, a partition comprising two plates slidably mounted in the casing longitudinally of the shaft and embracing the faces of the disk, a rod slidably mounted in the margin of one plate longitudinally thereof having one end engaging the adjacent inner end of the second plate, and one upon the other end of the rod at substantially right angles to the rod, and a spring engaging the first plate in contact with the rod.

In testimony whereof I have affixed my signature in presence of two witnesses.

PETER J. FANNING.
